ARTHUR L. DUNCAN, OF FRUITVALE, CALIFORNIA, ASSIGNOR OF ONE-THIRD TO CHARLES E. FORRY AND ONE-THIRD TO E. H. DUNCAN, BOTH OF FRUITVALE, CALIFORNIA.

EXHAUSTER.

1,132,172.

Specification of Letters Patent. Patented Mar. 16, 1915.

Application filed April 9, 1914. Serial No. 830,826.

To all whom it may concern:

Be it known that I, ARTHUR L. DUNCAN, a citizen of the United States, residing at Fruitvale, in the county of Alameda and 5 State of California, have invented certain new and useful Improvements in Exhausters, of which the following is a specification.

The present invention relates to an improvement in canning machinery and more particularly to an exhaust box through which the filled cans either open topped or with their partly attached covers are passed for the exhaust of the air therefrom, preparatory to the sealing and cooking thereof, and the present invention has for its principal objects to provide a device having concentric spiral trackways connected at one end and which are exceedingly simple and 10 inexpensive in construction, and along which the filled cans are caused to pass by independent pusher-bars; to provide a device in which the pusher-bars assist in maintaining the cans on the trackways; to provide means 15 for switching or transferring the cans from one trackway to the other; to provide means for continuously and automatically delivering filled cans to the apparatus and for removing the same therefrom after the air has 20 been exhausted therefrom.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be 35 resorted to without departing from the spirit or sacrificing any advantages of the invention.

To more fully comprehend the invention, reference is directed to the accompanying 40 sheet of drawings, wherein is disclosed one form of my invention, and in which—

Figure 1 is a vertical sectional view of the improved apparatus, disclosing the spiral rails, the mounting therefor and the pusher-bars coöperating therewith. Fig. 2 is a horizontal sectional view taken on line 2—2, Fig. 1, disclosing the can feed mechanism and the means for transferring or switching

the cans from one rail to the other at the junction point thereof.

Referring more particularly to the drawings wherein like characters of reference indicate corresponding parts throughout the several views, the numeral 1 designates a base plate which supports a suitable cylindrical housing 2 formed with a cover 3. A stationary shaft 4 is disposed vertically through the center of the housing and is mounted at its ends in the base plate 1 and the cover 3. Mounted within the cylindrical housing 2 on opposite sides of the supports 4 extending upwardly from the base 1 are the outer and inner oppositely disposed spiral trackways 5 and 6 which are substantially L-shaped in cross section and along 55 which the filled cans are propelled in a hereinafter described manner.

The outside upwardly inclined spiral trackway 5 leads from an opening 7 formed in the housing 2 and through which the cans 60 or other containers either open topped or with their covers partly clamped thereon are fed or introduced by the hereinafter described mechanism, and said outer trackway 5 connects at its upper end with the upper 65 end of the inside downwardly inclined spiral trackway 6, which terminates at its lower 70 end adjacent a discharge opening 8 formed in the housing 2 and through which the receptacles operated upon are discharged by 75 the hereinafter described mechanism.

The receptacles or containers are propelled along the respective trackways 5 and 6 by the outwardly and inwardly disposed vertically extending pusher-bars 9 and 10 80 which are substantially L-shaped in cross section and which are disposed adjacent the outer edge of the supporting portion of the respective trackways. The pusher bars 9 and 10 depend from an annular ring 11 provided on its inner edge with a downwardly projecting flange, provided on its inner surface with teeth 85 12, and said ring is supported by a disk 12' rotatable on the shaft 4 and retained in position adjacent the upper end 90 thereof by the hub portion of an arm 13 which is rigidly mounted on the shaft by the set screw 15. The lower ends of said outer pusher-bars 9 are connected by a ring 100 16, and the lower ends of said inner pusher-

bars 10 are connected by an annular member 17 formed on its inner face with teeth 18. The frame supporting the pusher-bars 9 and 10 is rotated by the pinion 19 and 20, which 5 intermesh respectively with the teeth 12 and 18, and are carried by a vertically disposed, rotatably mounted driven shaft 21, extending upwardly through the base plate 1 and the arm 13, and said shaft carries on its 10 lower end a beveled gear 22 which intermeshes with a corresponding gear 23 mounted on a power shaft 24.

It will be observed from Fig. 2 of the drawings, that the diameter of the cans or 15 receptacles is such as to overhang the lower supporting portion of the L-shaped trackways, and the cans or receptacles as positioned thereon are engaged in the rear and on their outer side by the oppositely disposed faces of the L-shaped pusher-bars, and said pusher-bars in their movement relative to the trackways retain the cans or 20 receptacles thereon. The above mentioned construction and arrangement of parts dispenses with the use of the slotted channel 25 trackways with the pusher-bars working between the same, which are now commonly in use, and enables an exhauster to be constructed which is considerably cheaper than 30 those of this type at present in use.

To perform the exhausting operation, steam is admitted into the housing 2 in any suitable manner, not necessary to be here shown, the steam forming the medium for 35 exhausting the air from the cans. The filled cans or receptacles are fed through the opening 7 onto the lower portion of the trackway 5 by the fingers 25 carried by a flexible endless chain 26, which operates 40 over a plate 27 extending laterally from one side of the base 1, and said plate carries a guide 28 between which and the chain 26 the cans are propelled. The endless chain 45 operates at one end around a sprocket 29 45 carried by the upper end of a shaft 30 journaled in a bearing 31 in said plate 27 adjacent the opening 7, and said shaft carries on its lower end a sprocket 32. The cans or 50 receptacles from which the air has been exhausted by the action of the steam thereon, are removed from within the casing 2 at a point adjacent the lower end of the trackway 6 and through the opening 8 by a rotary plate 33 onto which the cans or 55 receptacles are delivered from the lower end of the trackway 6 by the pusher-bars 10, and said plate is formed in its peripheral edge with a plurality of recesses 34 into which are received the outwardly extended edges 60 of the pusher-bars. The plate 33 is carried on the upper end of a shaft 35 rotatably mounted in a bearing 36 formed in the base 1 adjacent the opening 8, and said shaft carries at its lower end a sprocket 37. The 65 vertical portions of the upper ends of the L-

shaped trackways 5 and 6 are cut away and the horizontal portions at this point are connected in any suitable manner, as at 38 in Fig. 1, and at this point the filled cans or receptacles are transferred or switched 70 from the upwardly inclined spiral trackway 5 to the downwardly inclined trackway 6 by the hereinafter described mechanism. A transversely disposed plate 39 connects the upper end of each of the pusher-bars 9 and 10, and pivotally mounted, as at 40 to the upper outer side edge of each outer pusher-bar 9 in a plane slightly above the junction of the trackways 5 and 6, are the switching 75 or transferring arms 41, which project rearwardly from each pusher-bar to a point immediately in front of a succeeding pusher-bar, as in Fig. 2, adjacent the can or receptacle pushed thereby. The arms 41 are normally outwardly pressed by coiled compression springs 42 which are interposed between the inner side of the same and suitable brackets 43, and said arms are adapted on the rotation of the disk 12' to be forced 80 into contact with a cam surface 44 carried by the inner surface of the housing 2 adjacent one end of the juncture point 38 of the trackways 5 and 6, and to one side of a point A where the vertical side member of the inner track rail crosses the member 38. 85 As the arms 41 are forced inwardly, the same contact with the cans associated with the outer ends thereof and push or force the can from the outer pusher-bars 9 to the inner pusher-bars 10, the cans at this time 90 being propelled by the transverse plates 39. A drive sprocket 45 is carried by the lower end of the shaft 21 and the same operates 95 a chain 46 which extends around the sprockets 37, and 32, and an idler sprocket 46 100 rotatably mounted on the lower end of the shaft 4, and said chain drives the can feed and discharge mechanisms in the direction of the arrow—Fig. 2.

The device being assembled as in the 100 drawings, and power being applied to the shaft 24, the same is timed to operate in the following manner: The filled cans or receptacles either open topped or with their tops loosely secured thereon are deposited on the 115 runway 27 between the chain 26 and the guide 28, and said cans or receptacles are engaged by the fingers 25 and carried through the opening 7 onto the lower portion of the outer upwardly extending spiral 120 trackway 5. As the cans or receptacles are deposited on the trackway by the fingers 25, the same are each engaged in the rear and outer side by a pusher-bar 9 and are forced upwardly on said trackway to be acted on 125 by the steam in said housing and as the cans travel upwardly on said trackway, the same slide vertically on said pusher-bars. The cans on reaching the top of the outer concentric spiral trackway 5 are carried onto 130

the portion 38 and on reaching this point the same are acted on by the transferring arms 41 which force the cans inwardly from the outer pusher-bars 9 toward the 5 inner pusher-bars 10, and in their travel from the outer to the inner pusher-bars, the same are propelled by the plates 39. The transferring or inwardly pushing of the cans from the outer pusher-bars 9 toward 10 the inner pusher-bars 10 positions the same to contact with the vertical portion A of the inner concentric spiral track rail and said cans thus positioned are carried downwardly on said inner track-rail 6 by the 15 inner pusher-bars 10. The cans on reaching the lower end of the inner track-rail 6 are carried by the pusher-bars onto the rotating plate 33 which removes the filled cans or receptacles with the air exhausted therefrom 20 from within the housing through the discharge opening 8, and said cans or receptacles are removed from the plate by any suitable mechanism, not shown.

It will be apparent that the cans or receptacles may be allowed to remain in the exhauster for any given length of time and this is dependent upon the speed of the power shaft 24 which controls the speed of the feed and discharge mechanism, and the 30 operation of the pusher bars.

Having thus described my invention what is claimed as new and is desired to protect by Letters Patent is:—

1. In a device of the class described, a 35 housing, a can-way therein comprising a single substantially L-shaped trackway, a series of vertically disposed substantially L-shaped pusher-bars disposed adjacent the outer edge of the horizontal portion of said 40 single track-way, and means for operating said pusher-bars laterally to propel cans on said can-way.

2. In a device of the class described, the combination with a housing, two concentric 45 spirally arranged can-ways therein, the two being inclined in a direction opposite to each other and each formed of a single substantially L-shaped track-way, said track-ways communicating at one end, and means for 50 propelling cans along said track-ways.

3. In a device of the class described, the combination with a housing, two concentric spirally arranged can-ways therein, the two being inclined in a direction opposite to each 55 other and each formed of a single substantially L-shaped track-way, said track-ways communicating at one end, means for propelling cans along said track-ways, and means for shifting the cans from one track- 60 way to another at the joining point thereof while being propelled along said track-ways.

4. In a device of the class described, the combination with a housing, two substantially L-shaped oppositely disposed concentric spirally arranged single track-ways

therein for the conveying of cans, the two being inclined in a direction opposite to each other, and means for propelling the cans along said single track-ways.

5. In a device of the class described, the 70 combination with a housing, two substantially L-shaped oppositely disposed concentric spirally arranged single track-ways therein each adapted for the conveying of cans, the two being inclined in a direction 75 opposite to each other, means connecting said single track-ways at one end, means for conveying cans along said track-ways, and means for shifting the cans from one track-way to the other at the joining point thereof 85 while being propelled along the same.

6. In a device of the class described, the combination with a housing, two substantially L-shaped oppositely disposed concentric spirally arranged single track-ways 85 therein for the conveying of cans, the two single track-ways being inclined in a direction opposite to each other, a series of vertically disposed substantially L-shaped pusher-bars disposed adjacent the outer edge 90 of the horizontal portions of each of said single track-ways, and means for operating said pusher bars laterally to propel cans on said track-ways.

7. In a device of the class described, the 95 combination with a housing, two substantially L-shaped oppositely disposed concentric spirally arranged track-ways therein for the conveying of cans, the two being inclined in a direction opposite to each other, 100 means connecting said track-ways at one end, a series of vertically disposed substantially L-shaped pusher-bars disposed adjacent the outer edge of the horizontal portions of each of said track-ways, means for 105 operating said pusher-bars laterally to propel cans on said track-ways, and means carried by certain of said pusher-bars and operated on the operation thereof for shifting the cans from one track-way to the other at 110 the joining point thereof.

8. In a device of the class described, the combination with a housing, a pair of substantially L-shaped oppositely disposed spiral track-ways, one arranged within the 115 other and inclined in opposite directions, a shaft extending into said housing, a series of substantially L-shaped depending pusher-bars supported by said shaft and capable of rotation about the same, said pusher-bars 120 coacting with the outer edge of the horizontal portion of said track-ways and adapted on the operation thereof to advance cans up said outer track-way and down the inner track-way, means carried by each of said 125 pusher-bars for directing the cans from the upper end of the outer track-way to the inner track-way and from the path of travel of one row of pusher-bars into the path of travel of another row of pusher-bars. 130

9. In a device of the class described, the combination with a housing, a pair of single substantially L-shaped oppositely disposed spiral track-ways, one arranged within the other and inclined in opposite directions, a single supporting means common to both of said track-ways and to the opposite surfaces of which said single track-ways are secured, a series of vertically disposed pusher-bars 10 coöperating with each of said single track-

ways, and means for operating said pusher-bars laterally to propel cans on said track-ways.

In testimony whereof I have signed my name to this specification in the presence of 15 two subscribing witnesses.
